UNITED STATES PATENT OFFICE

FRANK T. COPE, OF SALEM, OHIO, ASSIGNOR TO THE ELECTRIC FURNACE COMPANY,
OF SALEM, OHIO, A CORPORATION OF OHIO

RESISTOR GRID.

Original application filed September 17, 1923, Serial No. 663,275. Divided and this application filed May 13, 1930. Serial No. 451,976.

This invention relates to electric furnaces and more particularly to the resistance elements for producing the heat in the furnace and has for its objects to provide a resistor heating grid formed of solid metal of a cross sectional shape to radiate the heat rays into the interior of the furnace at an angle to the furnace wall, and comprising a single bar bent into a plurality of parallel sections so proportioned as to produce a radiating surface considerably greater than the wall surface covered by the grid, means being provided for supporting the grid spaced from the furnace wall and in a manner to permit expansion and contraction of the grid without allowing the sections thereof to move out of their parallel relation to each other.

The above and other objects may be attained by constructing the resistor grid and supporting means in the manner illustrated in the accompanying drawings, in which—

Figure 1 is a front elevation of a resistor grid embodying one form of the invention, showing the same mounted upon a fragment of furnace wall;

Fig. 2, a section of the grid on the line 2—2, Fig. 1;

Fig. 3, a section of the grid on the line 3—3, Fig. 1;

Fig. 4, a section of the grid on the line 4—4, Fig. 1;

Fig. 5, a transverse sectional view through the wall showing an end elevation of the grid and the terminal thereof;

Fig. 6, a perspective view of the terminal stud;

Fig. 7, a front elevation of the terminal;

Fig. 8, a perspective view of one of the supporting hooks;

Fig. 9, a similar view of one of the lower spacing hangers; and

Fig. 10, the modified cross section of the grid, comprising the subject matter of this divisional application.

Similar numerals refer to similar parts throughout the drawings.

A portion of a furnace wall built of refractory brick or the like, is indicated at 1 and the resistor grid is formed of a con-

tinuous bar of metal bent at intervals to produce a plurality of vertical parallel portions 2 of the general cross sectional shape shown in Fig. 3, the curved upper ends thereof being preferably flattened as shown at 4, giving the cross sectional shape shown in Fig. 2, while the lower curved ends are provided with the depending studs 5.

The resistor grids may be made of cast, rolled or forged metal bars of substantial thickness, as shown in the drawing, and the general cross sectional shape of the grid may be T-shaped, as shown in Fig. 3, the base 6 having the inclined side edges 7, while the flange or rib 8 is tapered toward its point which is rounded as at 9.

It has been found, however, that a better casting can be made by providing two ribs, one at each side of the base, which also gives a greater radiating surface on the ribbed side of the grid, so that a preferred general cross sectional shape of the grid is substantially channel shape, as shown in Fig. 10, the base 6 and the flanges or ribs 8^a having inclined sides; and in either case the grid bar being flanged or ribbed to give it strength and rigidity.

With such cross sectional shape, the greater portion of the surface of the grid is located at an angle to the normal plane of the grid, thus radiating the majority of the heat rays into the heating chamber of the furnace at an angle to the furnace wall.

The grid is supported at its upper edge portion by the hooks 10 which engage the flattened portions 4 of the grid. Each hook is provided with the flattened shank 11 received in the flat socket 12 formed in the upper edge of the adjacent brick in the refractory wall 1, and depending lugs 13 and 14 are provided at the forward and rear ends of the shank to prevent longitudinal movement of the shank within the wall.

The depending studs 5 upon the lower ends of the grid bars are extended through the squared apertures 15 formed in the lower supports 16, which are also provided with the flat shanks 17 received in the notches 18 in the upper faces of the adjacent bricks.

A shoulder 19 is formed at the inner end of the shank and a depending lug 20 at the outer end thereof to prevent longitudinal movement of the support in the wall.

5 Each extremity of the grid is connected to a terminal stud 21 which is extended through a suitable opening 22 in the brick wall of the furnace, the inner end thereof being provided with the flat head 23 which 10 is welded to the adjacent extremity of the grid.

A terminal 24 is connected to the outer end of each of the terminal studs 21, having the split socket 25 which receives the end of 15 the stud, clamping bolts 26 clamping the same tightly upon the stud. Sockets 27 are formed in the terminal into which the ends of the cables 28 are soldered or otherwise connected.

20 Owing to the cross sectional shape of the grid and the conformation of the same, the radiating surface of the grid is equal to about twice the area of wall surface upon which the grid is mounted, thus producing a 25 maximum of heat from a given area.

By referring to Figs. 3 and 10, it will be seen that the cross sectional shape of the grid is such that the greater portion of the radiating surface is arranged to radiate the 30 heat rays inward toward the interior of the heating chamber of the furnace, and away from the furnace wall at an angle thereto, thus radiating considerably more heat into the interior of the heating chamber than is 35 possible with the usual constructions now in use.

As the studs 5 upon the lower ends of the grid bars are extended loosely through the openings 15 in the lower supports, the grid 40 may expand as the temperature of the same is increased, without causing any buckling or warping, since the entire weight of the grid is supported from the upper hooks.

The upper hooks engaging the loops at the 45 upper end of the grid and the lower supports engaging the studs upon the lower ends of the grid bars, prevent lateral distortion of the grid under high temperature, thus preventing adjacent portions of the 50 grid from coming into contact with each other when they are expanded by the heat.

The broad claims for the generic invention illustrated and described in said parent application, Serial No. 663,275, have been 55 transferred to this divisional application, so as to be joined with claims for the specific invention in which the generic invention was designed and developed.

The grid formed of substantially T- 60 shaped, cross sectional shape, with inclined sides, and with flat curved portions and supporting hooks engaging the same; and the combination of a wall, a resistor grid and supports extending entirely through the 65 wall; which are illustrated and described

but not claimed herein, are made the subject of claims in the parent application, Serial No. 663,275, from which this application is divided.

I claim:—

1. A resistor heating grid formed of a bar of substantial thickness of substantially channel shaped, cross sectional shape, bent upon itself to provide a plurality of vertical parallel portions connected at alternate ends 75 by curved portions. 70

2. A resistor heating grid formed of a bar of substantial thickness of substantially channel shaped, cross sectional shape, bent upon itself to provide a plurality of vertical parallel portions connected at alternate ends 80 by curved portions, the curved portions at the upper end of the grid being of substantially flat cross sectional shape and supporting hooks engaging said upper curved portions. 85

3. A resistor heating grid of the character described formed of a bar of substantial thickness of substantially channel shaped, cross section, the side faces thereof 90 being inclined to radiate the major portion of the heat rays away from the base in the direction of the ribbed side of the bar. 95

4. A resistor heating grid for a furnace comprising a metal bar of substantial thickness of substantially channel shaped cross sectional shape, with its sides inclined so as to provide a radiating surface which will radiate the major portion of the heat rays away from the furnace wall at an angle 100 thereto. 98

5. A resistor heating grid for a furnace wall comprising a metal bar of substantial thickness bent upon itself at intervals, the convolutions being so spaced and the bar 105 being of substantially channel shaped cross sectional shape, with its sides inclined so as to provide a radiating surface which will radiate the majority of the heat rays toward the interior of the heating chamber of 110 the furnace and of greater area than the wall surface covered by the grid. 110

6. A metal bar resistor heating grid of substantial thickness for electric furnaces consisting of a sinuous grid having straight legs of ribbed section connected at alternate ends by integral loops, some at least of said loops having integral prongs extending outwardly therefrom. 115

7. A metal bar resistor heating grid of substantial thickness for electric furnaces consisting of a sinuous grid having straight legs of ribbed section connected at alternate ends by integral loops. 120

8. A resistor heating grid made of bar metal of substantial thickness in serpentine shape, the body of the same including a base section and a longitudinal rib projecting from one side thereof. 125

9. A resistor heating grid made of bar 130

metal of substantial thickness and including a base section and a longitudinal rib projecting from one side thereof.

10. A resistor heating grid formed of a metal ribbed bar of substantial thickness bent upon itself to provide a plurality of vertical parallel portions connected at alternate ends by curved portions.

11. A resistor grid comprising a bar bent upon itself to form a plurality of parallel straight portions, means for supporting the grid at its upper end, depending studs upon the lower end of the grid and supporting guides provided with apertures loosely engaging the depending studs.

12. A resistor grid for a furnace wall comprising a solid metal bar of such cross sectional shape with its sides inclined so as to provide a radiating surface which will radiate the major portion of the heat rays away from the furnace wall at an angle thereto.

13. A resistor grid for a furnace wall comprising a solid metal bar bent upon itself at intervals, the convolutions being so spaced and the bar being of such cross sectional shape with its sides inclined so as to provide a radiating surface which will radiate the majority of the heat rays toward the interior of the heating chamber of the furnace and of greater area than the wall surface covered by the grid.

In testimony that I claim the above, I have hereunto subscribed my name.

FRANK T. COPE.
